UNITED STATES PATENT OFFICE

135,524

DESIGN FOR AN INFANT'S WEANING TRAY

Fleurette Crettaz Johnstone, Pasadena, Calif.

Application May 13, 1942, Serial No. 106,883

Term of patent 14 years

To all whom it may concern:

Be it known that I, Fleurette Crettaz Johnstone, a citizen of the United States, residing at Pasadena, in the county of Los Angeles and State of California, have invented a new, original, and ornamental Design for an Infant's Weaning Tray, of which the following is a specification, reference being had to the accompanying drawing, forming a part thereof.

Figure 1 is an edge elevational view of the infant's weaning tray, showing my design, looking at the forward edge thereof.

Figure 2 is a perspective view of the same.

The characteristic features of my design reside in an infant's weaning tray having the configuration illustrated, in which the bottom of the tray slopes gradually from the opposite sides to the center and the tray increases gradually in depth from the rear to the front thereof, all as shown in the drawing.

I claim:

The ornamental design for an infant's weaning tray, as shown and described.

FLEURETTE CRETTAZ JOHNSTONE.
